UNITED STATES PATENT OFFICE.

HORACE M. CAKE, OF PHILADELPHIA, PENNSYLVANIA.

AIR-COMPRESSOR.

1,316,139.

Specification of Letters Patent. Patented Sept. 16, 1919.

Application filed July 6, 1918. Serial No. 243,524.

To all whom it may concern:

Be it known that I, HORACE M. CAKE, a citizen of the United States, residing at Philadelphia, in the county of Philadelphia and State of Pennsylvania, have invented certain new and useful Improvements in Air-Compressors, of which the following is a specification.

This invention relates broadly to fluid compressors and particularly to a compressor for air, or the like.

The principal object of the invention is to provide a multi-stage compressor wherein the same amount of energy is utilized at each compression stage.

A still further object of the present invention is a multi-stage air compressor wherein the compressing elements are mounted for reciprocal action in such manner that the energy utilized in the compression action is equally distributed throughout all of the compression elements.

More specifically the present invention comprises an air compressor or the like as specified wherein power to the several compression elements is delivered through differential gearing in such manner that the energy from the driving shaft is distributed equally throughout all of the compression members.

Still more specifically the present invention comprises a compressor for air or the like wherein the air progresses in stages through the compressor and is gradually as the pressure is increased reduced in volume and with compression elements mounted at intervals in the device with the diameters of the compression elements in proportion to the pressure of the air so that pressure times the area of a compression element is a constant for each compression stage in the machine.

Other objects of the invention will in part be obvious and will in part be pointed out hereinafter in the specification following by reference to the accompanying drawings wherein is illustrated preferred forms of the present invention though it will be apparent that the invention may be practised in forms other than the specific disclosure herewith, so that it will be understood the specific disclosure is to be considered as illustrative and not to be taken in the limiting sense.

Throughout the drawings like characters are used to represent like parts in the several figures thereof.

Figure I illustrates one form of the invention with certain parts shown in cross-section.

Fig. II illustrates a slightly different construction wherein certain of the parts are also shown in cross-section.

Fig. III is a diagrammatic view illustrating the operation of the machine.

Heretofore in the art of air compressors, and the like, two systems have been in use, one comprising a multi-stage compressor wherein the compressing elements were fixedly or rigidly mounted to be positively driven with a definite speed ratio between the several compressing elements so that a rigid fixed relation was at all times maintained between the several compressing elements. The other type comprises a system wherein individual independent compressors carry the compression from one stage to the other. In this system no definite relation whatever is maintained between the several compressors; and it is the general practice in this type of system to utilize pressure or storage chambers for each stage of the compression operation so that at each stage the dynamic forces become a static pressure. Since conditions of the atmosphere, due to the varying barometric pressure, humidity, etc., are different for different times, it is obvious that a compressor of the first type, wherein the compression elements are rigidly connected can not at all times, and under all conditions, be working most efficiently for every stage of compression, so that the total efficiency of this type of compressor is low.

In the second type the efficiency is higher but it depends largely on regulation of the operation of the various compressors and this system introduces a loss at each stage where the air changes from dynamic to static pressure.

The present invention overcomes the difficulties of the prior art by providing a multi-stage compressor wherein each compression element is reciprocally driven relatively to every other pressure element in the compressor so that at all times each compressor must absorb the same amount, or proportion, of the total horse power driving the compres-

sor. Under these circumstances it is not necessary to provide static chambers between the compressing elements and therefore the forces delivered to the air do not change 5 from dynamic to static until the last and final stage of compression is passed. In view of the reciprocal relationship of the compressing elements it will be seen that each compressor is operating at the same efficiency 10 as every other compressor in the machine.

Referring now to the drawings and more especially to Fig. I the driving shaft 1 carrying the drive wheel 2 is mounted in suitable bearings 3 and 4 which are carried 15 by a casing 5 that is illustrated in this figure as being conical, and of such proportions and dimensions as will be referred to later. This driving shaft 1 carries a header 6 upon which are mounted the main compensating 20 gears 7. These compensating gears 7 mesh with beveled gears 8 and 9, one of which is carried on the tubular shaft 10 and the other of which is carried on the tubular shaft 11 so that the gears 7, 8, and 9 comprise 25 the main differential gearing A. These tubular shafts 10 and 11 are mounted to rotate on the main shaft 1. The tubular shaft 10 carries a sub-header 12 and the tubular shaft 11 carries a sub-header 13. The sub- 30 header 12 has mounted thereon sub-compensating gears 15 and the sub-header 13 carries sub-compensating gears 16. The sub-compensating gears 15 mesh on one side with a bevel gear 17 on the tubular shaft 18 and 35 these gears 15 mesh on the other side with a bevel gear 19 on the tubular shaft 20, all of which comprises the secondary differential gearing B. The shaft 18 is mounted to freely rotate over the shaft 10 and the shaft 40 20 is mounted to freely rotate on the main shaft 1. The sub-compensating gears 16 in a similar manner mesh on one side with a bevel gear 21 on the tubular shaft 22 and these gears 16 mesh on the other side with a bevel gear 23 on the tubular shaft 25, and 45 thus comprise the secondary differential gearing C. The tubular shaft 22 is mounted to freely rotate on the shaft 11 while the tubular shaft 25 is mounted to freely rotate 50 on the driving shaft 1. The shaft 20 carries the first stage compressor fan 26; the shaft 18 carries the second stage compressor fan 27; the shaft 22 carries the third stage compressor fan 28; and the shaft 25 carries the 55 fourth stage compressor fan 29. It is to be noted that the compressor fans diminish in size and therefore, in area, from the first to the last stage. The casing 5 follows the diminishment of diameter of the fans so 60 that this casing is conical, as shown in Fig. I. The diameters of the compressor fans are preferably so proportioned that under normal conditions where air is to be compressed from standard barometric pressure 65 to a predetermined static pressure, the same

rotation for each fan will deliver the same energy throughout the system. Since barometric pressure varies it is obviously impossible to maintain ideal conditions at all times with a rigid structure wherein the 70 fans are properly proportioned for a definite starting pressure. In the present construction, however, the differential gearings compensate for variations from definite predetermined initial pressures so that the horse 75 power delivered at each stage of the compressor is most effectively delivered under ideal conditions.

Referring to Fig. II the structure of a driving element is substantially the same as 80 that disclosed in Fig. I. The casing, however, is somewhat different in that each stage of the compressor is inclosed in a cylindrical part comprising a section of a whole casing so that for this type of compressor the casing is made up of cylindrical sections 30. In order to eliminate air loss from the ends of the fan blades the blades are inclosed in bands or hoops 31 and filler blocks 32 are provided on the interior of the casings adjacent the bands 31 so that there is no tendency of the air (which has assumed the condition of being under static pressure) to escape between the bands 31 and the side wall of the casings 30. 85

In operation of this air compressor the power is transmitted through the drive wheel 2 to the main shaft 1 and one-half the power is transmitted from the main compensating gears or main differential A, to 100 the tubular shaft 10 while the other half of the power is transmitted through these compensating gears or differential to the tubular shaft 11. The energy in the tubular shaft 10 is likewise divided by the secondary differential gearing B so that one-half of this energy, or one-fourth of the total energy is transmitted to the compressor fan 26 and the other one-fourth of the total energy is transmitted to the compressor fan 27. In 105 like manner the energy in the tubular shaft 11 is divided by the differential gearing C between the compressor fans 28 and 29. By this construction it is to be noted that each compressor fan at all times receives one-fourth of the total driving energy and if for any reason there is a tendency of one compressor fan to receive more energy than another, the differential gearings A, B, and C immediately distribute this excess energy 110 among the other fans so that at substantially all times each fan absorbs the same amount of energy. The number of fans may be increased or decreased as the conditions under which the machine is to operate may require, so long as the compensating relation between the several fans is maintained. 115

I claim—

1. An air compressor or the like comprising in combination a driving shaft, compen- 120

- 5 sating gears carried by said driving shaft, multiple compressor members mounted for rotation about the said driving shaft, compensating means operatively connecting all of said compressor members with the said compensating gears to drive all of said compressor members in the same rotative direction, and a casing inclosing said compressor members.
- 10 2. In an air compressor or the like the combination of a driving shaft, compensating gearing operatively connected with said driving shaft, a plurality of compressor members mounted for rotation about said driving shaft, and means operatively connecting said compressor members with said compensating means, and a casing inclosing said compressor members.
- 15 3. In an air compressor or the like the combination of a driving shaft, a plurality of compressor fans mounted for rotation about said shaft, a casing surrounding said compressor fans, and compensating means connecting said compressor fans with said driving shaft in such manner that the rotation of each fan is dependent upon the resistance offered by the other fans.
- 20 4. In an air compressor or the like, the combination of a driving shaft, multiple compressor fans mounted upon said driving shaft, a casing surrounding said fans, and compensating means operatively connecting said driving shaft with each of said fans to drive all of the said fans in the same rotative direction and in such manner that each fan is adapted to deliver an equal amount of the power received from said driving shaft.
- 25 5. In an air compressor or the like the combination of a driving shaft, multiple compressor fans mounted for rotation around said driving shaft, a casing surrounding said fans, and compensating means operatively connecting said fans with said driving shaft to drive all of the said fans in the same rotative direction and in such manner as to equalize the effective forces delivered by each fan.
- 30 6. In an air compressor or the like the combination of a driving shaft, compression mechanism carried by said driving shaft, said compression mechanism comprising compression fans rotatable upon said shaft, and compensating means for permitting certain of said fans to rotate at a speed different from that of the driving shaft.
- 35 7. In a compressor for air and the like the combination of a driving shaft, multiple fans mounted to rotate upon said driving shaft, the blades of each fan being pitched in the same direction, means to cause each fan to deliver an equal portion of the energy transmitted by the driving shaft, and a casing inclosing said fans.
- 40 8. In a device for compressing air or the like, the combination of a driving shaft, a plurality of compressor fans mounted to rotate on said driving shaft, differential gearing carried by said driving shaft and co-operating with said fans to transmit energy from said shaft to said fans, and a casing surrounding said fans.
- 45 9. In an air compressor or the like the combination of a driving shaft, a plurality of fans rotatably mounted on said driving shaft, a differential gearing mounted on said driving shaft, gear mechanism connected with each of said fans and co-operating with said differential mechanism to drive said fans in the same rotative direction as the driving shaft, and a casing surrounding said fans.
- 50 10. An air compressor or the like comprising in combination a driving shaft, a plurality of compressor fans mounted for rotation about said driving shaft, said compressor fans decreasing in diameter from the inlet end of said compressor to the outlet end thereof, operative means connecting said compressor fans with said compensating mechanism to drive all of said compressor fans in the same rotative direction, and a casing surrounding said fans.
- 55 11. In an air compressor or the like the combination of a driving shaft, a differential gearing carried by said driving shaft, tubular shafts rotatably mounted on said driving shaft and being connected to said differential gearing, secondary differential gearings connected with said tubular shafts, and compressor fans operatively connected with said secondary differential gears.
- 60 12. In an air compressor or the like the combination of a driving shaft, a plurality of compressor fans mounted to rotate around said driving shaft, a casing surrounding said compressor fans, the inlet end of said casing being larger than the outlet end thereof, and the diameter of the said compressor fans being proportionate to the air pressure adapted to be maintained within the casing adjacent the fans when the device is in operation, and compensating means operatively connecting all of said fans with said driving shaft.
- 65 13. An air compressor comprising in combination a driving shaft, a plurality of air compressing means mounted to rotate around said driving shaft, a plurality of differential gears operatively connecting each of said fans with said driving shaft, and a casing surrounding said compressor members.
- 70 14. In an air compressor or the like the combination of a plurality of dynamic compressors, a driving shaft, and a plurality of differential gear mechanism operatively connecting each air compressor with the driving shaft in such manner that the driving force transmitted from the driving shaft to

each compressor is equal to the driving force transmitted to any other compressor in the machine.

15. In an air compressor or the like the combination of a plurality of air compressing means, a casing surrounding said air compressing means, driving means, and compensators between said air compressing means and said driving means whereby the force from said driving means is at all times equally distributed among all of said air compressing means.

16. In an air compressor or the like the combination of a casing providing an air passage way, a plurality of fans mounted within said casing, a driving shaft extend-

ing lengthwise of said casing, and compensating means whereby all of said fans absorb the same amount of horse power from the driving shaft.

17. In an air compressor or the like the combination of a casing having a large inlet end and a smaller outlet end, a plurality of air compressing means mounted within said casing, and driving devices for said means operatively connected thereto in such manner that each of said means at all times absorbs the same amount of driving energy whereby the driving force is equally distributed throughout all of said means.

HORACE M. CAKE.
